US00D879828S

(12) **United States Design Patent** (10) Patent No.: **US D879,828 S**
Höhne et al. (45) Date of Patent: **** Mar. 31, 2020**

- (54) **DISPLAY SCREEN OR PORTION THEREOF WITH GRAPHICAL USER INTERFACE**

(71) Applicant: **Apple Inc.**, Cupertino, CA (US)

(72) Inventors: **Sascha Höhne**, Hamburg (DE);
Gerhard Lengeling, Los Altos, CA (US); **Alexander Harry Little**, Woodside, CA (US); **Eli T. Manjarrez**, Sunnyvale, CA (US)

(73) Assignee: **Apple Inc.**, Cupertino, CA (US)

(**) Term: **15 Years**

(21) Appl. No.: **29/693,468**

(22) Filed: **Jun. 3, 2019**

Related U.S. Application Data

- (63) Continuation of application No. 29/676,190, filed on Jan. 9, 2019, now Pat. No. Des. 855,646, which is a continuation of application No. 29/660,093, filed on Aug. 17, 2018, now Pat. No. Des. 842,891, which is a continuation of application No. 29/594,423, filed on Feb. 17, 2017, now Pat. No. Des. 829,763, which is a continuation of application No. 29/552,028, filed on Jan. 19, 2016, now Pat. No. Des. 781,907.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee. The sole FIGURE shows a display screen or portion thereof with graphical user interface showing our new design. The peripheral dashed broken lines represent a display screen or portion thereof, which forms no part of the claimed design.
